UNITED STATES PATENT OFFICE

2,290,650

CIRCUIT CONTROLLER

Harold S. Ogden, Erie, Pa., assignor to General
Electric Company, a corporation of New York

Application June 5, 1941, Serial No. 396,679

5 Claims. (Cl. 171—312)

My invention relates to circuit controllers and particularly to electro-pneumatically controlled switching mechanisms for the series field of a dynamo-electric machine.

In Diesel-electric power systems it is known to use the main generator as a motor to crank the internal combustion engine. In such systems it has also been found advantageous to provide the main generator with a multiple section series field in combination with control means for cutting out a portion or all of the series field for full throttle operation. It has been found that the provision of a relatively large main generator series field during accelerating operation of the vehicle prevents racing of the internal combustion engine at low vehicle speeds and produces other advantageous system operating characteristics. Such a power system is described and claimed in a co-pending application of John C. Aydelott, Serial Number 396,685, filed June 5, 1941, and assigned to the same assignee as the instant application. The present invention relates to a switching mechanism for controlling the generator series field in such a power system.

Accordingly, the principal object of my invention is to provide a simple and inexpensive switching system and mechanism for changing the series field connections of a dynamo-electric machine while the machine is in operation.

It is a specific object of my invention to provide an electro-pneumatic series field switching mechanism for controlling the series field connections of a dynamo-electric machine in a plurality of steps while the machine is in operation and without interrupting the flow of power through the machine.

To the attainment of the foregoing and other objects and advantages, my invention is preferably embodied in the detailed construction to be hereinafter more fully described and claimed and is illustrated in the accompanying drawing in which Fig. 1 is a side elevation of my circuit controller; Fig. 2 is a sectional view taken along the line 2—2 of Fig. 1 looking in the direction of the arrows; Fig. 3 is a sectional view taken along the line 3—3 of Fig. 1 looking in the direction of the arrows; Fig. 4 is a sectional view taken along the line 4—4 of Fig. 1 looking in the direction of the arrows; Fig. 5 is a schematic diagram of the pneumatic operating system for my circuit controller; and Fig. 6 is a simplified circuit diagram of connections showing my circuit controller arranged to control the series field of a dynamo-electric machine.

Referring now to the drawing, my circuit con-

troller comprises a support 10 preferably made of cast metal and formed to provide pneumatic cylinders 11 and 12 adjacent each other in parallel relation and having a pair of integrally formed upright supporting members 13 and 14 at opposite ends of the cylinder block. The lower ends of the pneumatic cylinders are closed by a plate 15 connected to the casting 10 by a plurality of bolts 16. A contact supporting bridge 17, preferably made of a molded insulating material, is positioned above the pneumatic cylinders 11 and 12 between the upper ends of the supports 13 and 14. The support 17 has attached thereto a pair of fixed contacts 18 and 19 connected to terminal blocks 25 and 26, respectively. As shown in Fig. 2 the contacts 18 and the terminal block 25 are connected to the support 17 by a bolt 27 countersunk from the top of the support 17. The contact 19 is similarly connected to the support 17. A block of insulating material 28 mounted upon the casting 10 between the cylinders 11 and 12 carries a fixed contact 29 connected to a terminal block 30. The terminal blocks 25, 26, and 30 are preferably threaded as indicated at Figs. 1 and 2 to provide means for connection of external conductors. For mounting the controller upon a support a pair of brackets 31, 32 are secured to the support 17 in any suitable manner. The casting 10 is provided with bosses 33 bored and threaded for attachment of a suitable cover plate.

Each of the cylinders 11 and 12 is provided with a pneumatic piston of similar construction. At Fig. 2 is shown the piston 35 located in the cylinder 12. The piston 35 is bolted to a connecting rod 36 which is supported in a guide bearing 37 formed in the cylinder head and is provided on its high pressure lower side with a packing disk 38. A compression spring 39, which engages the upper side of the piston and the under side of the cylinder head, biases the piston to its lowermost position within the cylinder. The connecting rod 36 carries at its upper end a block of insulating material 40 to which is connected a movable contact 41 by any suitable means such as a bolt 42.

Referring now particularly to Figs. 1 and 3, a connecting rod 43 carried by the piston located in the cylinder 11 and similar in form to the connecting rod 36 has pivotally mounted at the top thereof a floating lever 44. The floating lever 44 is preferably formed of electrically conducting material and carries at its one end a movable normally open contact 45 and at its other end a movable normally closed contact 46. That end

of the floating lever 44 which carries the normally closed contact 46 is biased downwardly by a compression spring 50 positioned between the upper side of the floating lever 44 and the supporting member 17. As shown at Fig. 1 the member 17 is preferably bored to permit the use of a reasonably long compression spring even though the support 17 is positioned closely adjacent to the floating lever 44 for spaced considerations. As indicated at Fig. 2 the support 17 may be bored completely through so that the compression spring 50 engages a strip 51 of electrically conducting material firmly connected to the top of the supporting bridge 17. Since in my preferred circuit arrangement the metallic strip 51 is permanently electrically connected to the movable normally closed contact 46, engagement of the spring 50 with the strip 51 is not objectionable.

As clearly shown in Fig. 2, straps 52 and 53 of flexible electrically conducting material make permanent electrical connection between the conducting strip 51 and the movable normally closed contact 46 and between the conducting strip 51 and the movable contact 41, respectively.

Referring now to Figs. 2, 3 and 4, a pair of valve blocks 60 and 61 are bolted one above the other to the rear side of the casting 10 as by bolts 54 in order to control the admission of air to and the exhaustion of air from the pneumatic cylinders 12 and 11, respectively. As clearly indicated at Fig. 4 the valve block 61 is connected at one end to an electromagnet core 62 upon which is wound an actuating coil 63. In like manner the valve block 60 is provided with an electromagnetic actuating means including a coil 64. The actuating coils 63 and 64 are fitted with terminal connectors 64a, as best shown at Fig. 3. Since the valve blocks and their electromagnetic actuating means are of similar construction, only the block 61 shown in Fig. 4 will be described in detail. As may be seen at Fig. 4, the electromagnet 62-63 is provided with an armature 65 pivotally mounted upon a support 66 bolted to the valve block 61. The electromagnet core 62 is centrally bored to receive a valve operating rod 67 formed to provide a pair of needle valves 68 and 69 within the valve block 61. A compression spring 70 having one end seated against an adjusting screw 71 biases the needle valve assembly to open the valve 68 and to close the valve 69.

The casting 10 is provided with an inlet port 75 for connection to a main source of compressed air supply, and each valve block 60, 61 is provided with an atmospheric vent 76. As shown at Fig. 4, and as more fully indicated diagrammatically at Fig. 5, the casting 10 and the valve blocks 60 and 61 are provided with suitable passages for supplying compressed air from the inlet port 75 to each of the pneumatic cylinders 11 and 12 and for exhausting air from each of the cylinders to their respective atmospheric vents 76. Specifically, the inlet port 75 is connected to the valve block 61 by a passageway 80 and to the valve block 60 by a passageway 81. An inlet and exhaust passageway 82 connects the valve block 61 with the lower end of the pneumatic cylinder 11. An inlet and exhaust passageway 83 connects the valve block 60 with the lower end of the pneumatic cylinder 12. In order to avoid compression of air above the pneumatic pistons when compressed air is admitted to the lower sides thereof, the cylinders 11 and 12 are pro-

vided at their upper ends with atmospheric vents 84 and 85, respectively.

My new and improved circuit controller is preferably connected to the series field of a dynamo-electric machine in the manner shown schematically at Fig. 6. At Fig. 6 I have shown a main generator 90 having a shunt field 91 and a series field 92 connected through a line contactor 93a to a load circuit including an electric motor 93. Connected across the shunt field 91 and a field resistor 94 for engine cranking operation I have shown a battery 95 and a manually operable starting switch 96. Preferably the series field 92 is divided into a main central portion including the major part of the series field winding and two small auxiliary end portions 97 and 98. The auxiliary portion 97 of the series field winding is used only during engine cranking operation and in series with the main portion of the field. The portion 98 of the series field is permanently in the power circuit during generating operation and is unaffected by the operation of my circuit controller. The main central portion of the series field 92 is connected to be shunted through a series circuit including both the normally open and the normally closed contacts 45 and 46, respectively, carried by the floating lever 44. The normally closed contacts 29 and 46 are connected to be shunted by the normally open contacts 18 and 41 of the circuit controller through a resistor 99.

For actuation of the pneumatic pistons in the desired time relation, I have shown at Fig. 6 a manually operable controller 100 comprising a pair of cams 101 and 102 arranged to actuate a pair of cam switches 103 and 104 respectively. As indicated at Fig. 6 closure of the cam switch 103 completes an energizing circuit for the actuating coil 63 thereby to raise the floating lever 44, while closure of the cam switch 104 completes an energizing circuit for the actuating coil 64 thereby to raise the movable contact 41. The cam segments 101 and 102 on the controller drum 100 are arranged in overlapping relation so that the cam switch 104 will be closed before the cam switch 103 is open. Thus, in the "first position" of the controller 100, only the cam switch 103 is closed and air is admitted only to the cylinder 11, in the "full on" position of the controller only the cam switch 104 is closed and air is admitted only to the cylinder 12, but in passing from the "first position" to the "full on" position air is admitted to the cylinder 12 before the air is exhausted from the cylinder 11. Thus, the pneumatic pistons are operated sequentially in overlapping time relation. In operation, the generator 90 may be used to crank the engine by closing the starting switch 96. Since at the time the cam switches 103 and 104 are open, the pistons 11 and 12 are not actuated and only the contacts 29, 46 are in engagement. A starting circuit is thus completed from the battery 95 through the starting switch 96, the shunt field 91 and the resistor 94, and in parallel through the generator 90, the contacts 29, 46 and the portions 92 and 97 of the generator series field

To initiate acceleration of the vehicle the controller 100 is moved from its "idling" position to its "first position" and the line contactor 93a is simultaneously closed to connect the motor 93 to the generator 90. With the controller 100 in its "first position" the cam switch 103 is closed to complete an energizing circuit for the actuating coil 63 to actuate the valve 61. Actuation of the valve 61 completes a connection through the pas-

sage 82 between the inlet port 75 and the pneumatic cylinder 11. The application of air pressure to the lower side of the pneumatic piston in the cylinder 11 raises the connecting rod 43 and moves the contact 45 on the floating lever 44 into engagement with the stationary contact 19. During movement of the contact 45 the opposite end of the lever 44 which carries the contact 46 remains stationary due to the pressure exerted by the compression spring 50. As the upward movement of the connecting rod 43 continues after the contact 45 engages the contact 19, the contact 46 is separated from the stationary contact 29 against the bias of the spring 50. Thus, the movable contacts 45 and 46 respectively engage and disengage their cooperating fixed contacts sequentially, first to shunt the main portion of the series field 92 and then to connect it in series with the motor circuit. Thus in the first position of the controller 100, the generator series field includes the main section of the field and the small auxiliary section 98.

If the manual controller 100 is now moved to its "full on" position the cam switch 104 is first closed by the cam segment 102 to complete an energizing circuit for the actuating coil 64, and subsequently the cam switch 103 is opened by the cam segment 101 to disable the actuating coil 63. Actuation of the valve 60 applies air pressure to the pneumatic cylinder 12 and raises the piston 35 to close the contacts 41 and 48. Closure of the contacts 41 and 48 shunts the main portion of the series field winding 92 through the resistor 99. Subsequent deenergization of the actuating coil 63 vents the cylinder 11 to atmosphere through the passageway 82 and allows the floating lever 44 to return to its normal deenergized position. In moving back to its deenergized position, the lever 44 first closes the contacts 29 and 46 completely to short circuit the main portion of the series field winding, and then opens the contacts 19 and 45, to disconnect the main portion of the series field winding from the motor circuit and to complete a new motor circuit through the contacts 29 and 46 and the small auxiliary portion 98 of the series field winding.

Although I have shown and described but one preferred embodiment of my invention by way of illustration, many modifications will occur to those skilled in the art. I, therefore, wish to have it understood that I intend by the appended claims to cover all such modifications as fall within the true spirit and scope of my invention.

What I claim as new and desire to secure by Letters Patent of the United States is:

1. A circuit controller for the series field winding of a dynamo-electric machine comprising a plurality of fixed contacts, a floating lever provided at one end with a movable normally closed contact and at the other end with a movable normally open contact for cooperation each with one of said fixed contacts, spring means connected to one end of said lever to bias said movable contacts to their normal positions, first operating means connected to said floating lever intermediate its ends, means for connecting said normally open and normally closed contacts in series across said series field winding, a movable contact member cooperating with a third fixed contact, second operating means for said movable contact member, connections for shunting said normally closed contacts through said third fixed contact and a resistor, and control means for actuating said first and second oper-

ating means sequentially in overlapping time relation.

2. A circuit controller for the series field winding of a dynamo-electric machine comprising a support formed to provide a pair of pneumatic cylinders, a pair of pneumatic pistons slidably mounted in said cylinders, a floating lever connected to one of said pistons, a pair of movable contacts mounted at opposite ends of said lever, a first fixed contact positioned normally to engage one of said movable contacts, a second fixed contact positioned in normally spaced relation to the other of said movable contacts, spring means engaging one end of said lever to bias said movable contacts for sequential operation thereby to insure that at least one of said movable contacts is in engagement with its cooperating fixed contact at all times, means for connecting said fixed and movable contacts in series circuit relation across at least a portion of said series field winding, a third fixed contact, a third movable contact connected to said other piston in normal spaced relation to said third fixed contact, connections for shunting said normally engaged movable contact through said third movable contact and a resistor, valve means for admitting air to and exhausting air from said cylinders, and electromagnetic control means for actuating said valve means sequentially in overlapping time relation.

3. A circuit controller for the series field winding of a dynamo-electric machine comprising a support formed to provide a pair of pneumatic cylinders, a pair of pneumatic pistons slidably mounted in said cylinders, a floating lever connected at its center to one of said pistons, a plurality of fixed contacts mounted upon said support above said cylinders, a movable normally closed contact mounted upon one end of said floating lever normally to engage one of said fixed contacts, a movable normally open contact mounted upon the other end of said lever in normal spaced relation to a second of said fixed contacts, a compression spring engaging one end of said floating lever to maintain said normally closed contact in engagement with its cooperating fixed contact until said normally open contact engages its cooperating fixed contact, means for shunting said series field winding through a series circuit including said normally open and said normally closed contacts, a movable contact member connected to the other of said pistons for engagement with a third of said fixed contacts upon actuation of said piston, means for shunting said normally closed contacts through a series circuit including said movable contact member and a resistor, valve means for admitting air to and exhausting air from said pneumatic cylinders, electromagnetic means for actuating said valve means, and manually operable control means for energizing said electromagnetic means sequentially in overlapping time relation.

4. A circuit controller for the series field winding of a dynamo-electric machine comprising a cast frame formed to provide a pair of pneumatic cylinders in parallel spaced relation and a pair of upright end supports, a bridging support of insulating material carried by said end supports above said cylinders, a pair of pneumatic pistons in said cylinders, a floating lever pivotally connected at its center to one of said pistons, a pair of movable contacts mounted at opposite ends of said lever, a first fixed contact mounted upon said frame and positioned normally to engage one

of said movable contacts, a second fixed contact mounted upon said bridging support and positioned in normally spaced relation to the other of said movable contacts, a compression spring engaging said floating lever adjacent said normally engaged movable contact to bias said movable contact for sequential operation thereby to insure that at least one of said movable contacts engages one of said fixed contacts at all times, means for connecting said fixed and movable contacts in series circuit relation across at least a portion of said series field winding, a movable contact member connected to the other of said pistons in normal spaced relation to a third fixed contact carried by said bridging support, means for shunting said normally engaged contacts through a circuit including said movable contact member and a resistor, a pair of valve blocks mounted upon said frame to control said pistons, said frame and said valve blocks being provided with a plurality of interconnecting passageways, a pair of electromagnets mounted upon said valve blocks, each of said electromagnets having an armature operatively connected to a movable valve member formed to provide a plurality of needle valves, and a manually operable

controller for energizing said electromagnet sequentially in overlapping time relation.

5. In combination a dynamo-electric machine having a series field winding, switching means for said series field winding comprising a floating lever pivotally mounted at its center and carrying at its opposite ends normally closed and normally open contacts, connections between said contacts and said winding for shunting said winding and for connecting said winding in circuit with said machine through said contacts, actuating means for said switching means arranged sequentially to close said normally open contact and to open said normally closed contact thereby first to shunt said series field winding and to connect it in circuit with said machine and subsequently to unshunt said winding, said switching means being arranged for reverse operation upon disabling of said actuating means, 20 and second switching means actuatable prior to disabling of said actuating means to shunt said series field winding through a resistor, whereby said series field winding may be inserted and gradually disabled without interrupting the circuit of said machine.
